(57) **CLAIM**

The ornamental design for a portable game machine, as shown and described.

DESCRIPTION

FIG. 1 is a perspective view of a portable game machine showing our new design;

FIG. 2 is a top plan view thereof;

FIG. 3 is a front elevation view thereof;

FIG. 4 is a rear elevation view thereof;

FIG. 5 is a left side elevational view thereof;

FIG. 6 is a right side elevational view thereof;

FIG. 7 is a rear elevational view thereof; and,

FIG. 8 is a top plan view thereof, shown partially open position to expose a set of connectors.

The broken lines immediately adjacent to the claimed areas in the views represent the boundaries of the design. The broken away symbols indicate no specific length and the broken away symbols in the drawings indicate that any portion of the article beyond what is shown forms no part of the claimed design. Other broken lines indicate environmental features of the design. None of the broken lines form any part of the claimed design.
